UNITED STATES PATENT OFFICE.

EARLE B. BARTLETT, OF CHICAGO, ILLINOIS, ASSIGNOR TO W. W. KIMBALL COMPANY,
OF CHICAGO, ILLINOIS, A CORPORATION OF ILLINOIS.

SELF-PLAYING PIANO.

936,851.

Specification of Letters Patent. Patented Oct. 12, 1909.

Application filed March 15, 1909. Serial No. 483,355.

To all whom it may concern:

Be it known that I, EARLE B. BARTLETT, a citizen of the United States, residing in Chicago, in the county of Cook and State of Illinois, have invented a new and useful Improvement in Self-Playing Pianos, of which the following is a specification.

This invention relates to pianos and similar instruments provided with means whereby they may be played automatically at will and its object has been to provide the levers which control the automatic mechanism with a device whereby the same may be covered when not in use and with convenient devices for operating such cover.

The nature of the invention I have fully disclosed below and will be understood from the accompanying drawings in which—

Figure 1 is a front elevation of the keyboard of a piano equipped with my invention; Fig. 2 is an enlarged partial section on line 2—2 of Fig. 1 and Fig. 3 is a perspective of a portion of the folding lid or cover used to cover the controlling levers of the automatic playing mechanism.

In equipping a piano with my invention, the controlling levers of the automatic playing mechanism are arranged above the bed rail 3 of the keyboard in the usual manner, one of the levers being shown at 4 in Fig. 2. A recess 5 is formed in the bed rail and adjacent parts into which the operating ends of the levers are extended as seen at said figure. Above the recess 5 is a folding section 6 of the key slip 7. It is provided with a horizontal ledge 8 in front so that when closed as in Fig. 2 it covers the open top of the recess and conceals the controlling levers 4. This key slip section is hinged at 9 upon pivots projecting from its ends and extending into the adjacent parts of the key slip. By rocking this movable section 6 upon its pivots to the dotted position of Fig. 2, the recess 5 is uncovered so that access can be had to the controlling levers therein, and the movable section is operated to accomplish this by the hand lever 10 and a connecting bar 11 extending from said hand lever to the plate 12 secured upon the end of the movable section, the joints uniting said hand lever to the connecting bar and to the movable section all being pivotal ones. The hand lever is located beneath the keys 13

and within the bed rail and need not be visible from the outside of the instrument. 55 It is a swinging lever and is attached to a hinged bar 14 adapted to be turned from the position shown in Fig. 2 to the dotted position in said figure. When thus turned to the dotted position it sets close under the 60 keys and locks them against movement so that at such times no manual playing can be done. In this change of position of the locking bar 14 which is accomplished by the hand lever, the movable section 6 is also 65 opened so that the automatic playing mechanism can then be used. By reversing the hand lever the movable section 6 is closed and the key locking bar is turned down so as to release the keys. 70

By this construction while the piano may be used either manually or automatically as desired yet when the automatic mechanism is in use the keys are locked stationary, and when the instrument is played manually the 75 automatic levers are concealed and can not be used.

I claim:

1. The combination in a self playing keyboard instrument with the controlling levers 80 of the automatic playing mechanism, of a hinged section of the key slip concealing said levers, and a concealed hand lever below the keyboard mechanically connected to and operating said hinged section. 85

2. The combination in a self playing instrument with the keys and the controlling levers of the automatic mechanism, of a hinged bar for locking the keys while the automatic mechanism is in use, a hinged 90 front section of the key slip covering said controlling levers, and a hand lever concealed below the keyboard and connected to the bar and to said hinged section and actuating both simultaneously. 95

3. The combination in a self playing instrument with means for locking the keys and means for concealing the controlling levers of the automatic mechanism, of a single lever connected both to the locking means 100 and to the concealing means and operating them simultaneously.

EARLE B. BARTLETT.
